UNITED STATES PATENT OFFICE.

WILLIAM H. HAIGHT, OF NORTHFIELD, MINNESOTA.

MACHINE FOR SURFACING, SMOOTHING, AND POLISHING FLOORS AND OTHER LIKE SURFACES.

1,209,431.

Specification of Letters Patent. Patented Dec. 19, 1916.

Application filed February 17, 1915. Serial No. 8,750.

To all whom it may concern:

Be it known that I, WILLIAM H. HAIGHT, citizen of the United States, resident of Northfield, county of Rice, State of Minnesota, have invented certain new and useful Improvements in Machines for Surfacing, Smoothing, and Polishing Floors and other like Surfaces, of which the following is a specification.

10 The object of the invention is to provide a manually operated machine in which friction of the operating parts is reduced to a minimum, the parts being so assembled and adjusted with respect to one another that 15 the power applied to the abrading drum is as direct as possible in a machine of this type.

The invention consists generally in various constructions and combinations, all as 20 hereinafter described and particularly pointed out in the claims.

In the accompanying drawings forming part of this specification, Figure 1 is a side elevation, partially in section, of the machine embodying my invention, Fig. 2 is a plan view of the same, Fig. 3 is a modified form of the abrading roll.

The frame of the machine, or its main support, which I will designate by reference 30 numeral 2, is made of comparatively thin metal, substantially U-shaped in form, bent at right angles at the rear corners 3 and suitably reinforced. The shape and construction of the frame will allow the machine to be operated close to the walls of the room. The forward portion of the frame is downwardly turned, as indicated in Fig. 1, and has bearings for a shaft 4 on which the abrading rolls 5 are secured. The 35 ends of the shaft 4 fit within slots 6 provided in the frame 2 to allow the rolls to ride over high spots in the floor. The slots regulate the vertical movement of the rolls and if more than gravity is required to hold 40 the rolls in their working position, springs may be mounted on the frame in connection with the roll-supporting shaft. A small bearing roll 7 is preferably mounted in the forward portion of the frame below the 45 bearing of the abrading rolls, this bearing roll 7 being fixed as to vertical movement in the frame. An abrading roll, to act properly, must bear equally and evenly at each end. Should the power be applied at one 50 end only, the roll would bind and work un-

evenly, or, if it operated at all, the workmanship would be imperfect. If power should be applied at both ends, the drive mechanism would take up so much space that it would not be possible to run the 60 machine close to the walls of the room and additional gearing would be required. I therefore divide the abrading roll transversely in the center, making it in two sections of equal weight, and apply the power 65 directly to the center of the roll shaft, thereby distributing the application of power evenly to the roll, simplifying the construction and permitting the device to be operated close to the base boards. In carrying 70 out this idea, I mount a pinion 8 on the shaft 4 between the roll sections 5 and meshing with a gear 9, also mounted on a sleeve 9' carried by a shaft 10 having bearings in the side rails of the frame. The rear truck 75 wheels 11 are mounted on a shaft 12 that is mounted in hangers 13 pivoted at 14 in the side rails of the frame and is adjustable by means of thumb screws 15 mounted in the rear portion of the frame and engaging the 80 rear ends of the hangers for the purpose of changing the position of the truck wheels with respect to the frame and varying the friction of the abrading drums. Handle 85 bars 16 are pivoted at their lower ends to the shaft 10 and are secured in parallel relation with one another by suitable braces and vertical adjustment of these handle bars is permitted by means of curved bars 17 that are pivotally supported on the rear 90 portion of the frame and have notches 18 therein to engage cross rod 19 mounted in the bars 16. Side braces 20 are also provided, extending from the bars 16 to the 95 ends of the shaft 10 for the purpose of bracing the bars, distributing the strain on the shaft and strengthening the machine. A hand grip 21 is provided at the outer ends of the handle bars.

It will be noted that the greater weight of 100 the machine is in front of the rear supporting wheels, thereby providing for sufficient bearing of the abrading rolls on the floor, and when the frame and the handle bars are adjusted in their proper relative position 105 and secured by the notched brace, a slight bearing pressure on the hand grip 21 will serve to regulate the dressing tension of the rolls. By bearing down on the handle bars, it will be noted that the front of the ma- 110

chine may be raised and balanced on the rear wheels to permit its convenient movement from place to place. A frame 22 is adjustably mounted on the handle bars and 5 has bearings for a shaft 23 therein that is provided with an operating crank 24 and with a comparatively large sprocket wheel 25. A belt 26 connects this sprocket wheel 25 with a small wheel 27 on the shaft 28 that is 10 journaled in the lower portion of the handle bars. This sprocket wheel 27 has a clutch connection 29 with a gear wheel 30 that is provided with a balance or fly wheel 31, said gear wheel 30 meshing with a gear 9 to 15 drive the pinion 8 and the abrading rolls. When the crank is turned in the natural direction, the final power applied to the abrading rolls will tend to lift them rather than press them down, thereby preventing its 20 acting as a brake on the machine.

The smoothing rolls will generally be cushioned, as desired, and covered with a suitable abrading or smoothing material, such as sand paper, emery cloth, or polishing fabric, but in some instances, where the surface is very uneven or rough, it is desirable to provide a surface for the drum which will cut more readily than the sand paper. I have therefore shown in Fig. 3 25 the drums provided with a series of files or rasps 32, spirally applied to the drums at suitable intervals and made of comparatively thin material to fit the surface of the drums and have a solid bearing thereon, the 30 spaces between the files being adapted to receive the dust that is ground off in the operation and thereby prevent clogging, the dust working out at the ends of the rolls. These spiral plates may, if desired, be of uncut 35 blanks and the sand paper or other smoothing material may be fastened to these blanks in any suitable manner.

To operate the device, the crank 24 is revolved, the power transmitted through the 40 gearing to the drums, the ratio of the gearing being such that the drums will be rapidly revolved with a comparatively slow movement of the operating crank. The machine will be pushed over the floor, the 45 abrading drums touching lightly thereon, or heavily as high spots are encountered, as the machine is moved along or stopped at will. The construction of the frame and the mounting of the abrading rolls close to the 50 side rails of the machine allow the machine to be operated around the walls of the room close to the base board, while the center drive insures a maximum of power and its even 55 distribution and prevents any possibility of the rolls binding during the operation of the machine. Furthermore, comparatively short, independent rolls provide for a more uniform application of the roll surfaces to the 60 floor and produce better results where the 65 floor is uneven.

In various ways the details of construction herein shown and described may be modified and still be within the scope of my invention.

I claim as my invention:

1. A manually operated floor smoothing machine comprising a frame, rolls journaled therein having abrading surfaces, said rolls being of equal length and weight and arranged end to end, means for applying driving power to said rolls between their abutting ends and midway between the outer ends thereof, means supporting the rear portion of said frame and handle bars for said frame, the outer ends of said abrading rolls being adjacent to the outer faces of the side rails of said frame, whereby said rolls may be operated on the floor close to the base board.

2. A manually operated floor smoothing machine comprising a frame, rectangular, substantially, in form and a bearing roll mounted in the forward portion of said frame, smoothing rolls journaled in said frame in the rear of said bearing roll, hangers pivoted on the side rails of said frame in the rear of said smoothing rolls, carrying wheels mounted in said hangers and means for raising or lowering said hangers independently of one another to adjust the bearing of said smoothing rolls with respect to the floor surface.

3. A manually operated floor smoothing machine comprising a frame having side rails, a bearing roll mounted in the forward portion of said side rails, smoothing rolls journaled in the forward portion of said side rails in the rear of said bearing roll and adjacent thereto, hangers pivotally supported at their forward ends in said side rails, carrying wheels mounted in said hangers, thumb screws mounted in the rear portion of said frame and engaging the rear ends of said hangers for vertical adjustment thereof to raise or lower said carrying wheels with respect to the floor surface.

4. A manually operated floor smoothing machine comprising a frame having a rear end rail and substantially parallel side rails secured thereto, a bearing wheel mounted in the forward portion of said side rails, a shaft loosely journaled in the forward portion of said side rails and having freedom of vertical movement in its bearings in said rails, smoothing rolls arranged end to end on said shaft with a space between them and of substantially the same length and diameter, a driving mechanism geared to the middle portion of said shaft between said smoothing rolls, and suitable carrying wheels supporting the rear portion of said frame.

5. A manually operated floor smoothing machine comprising a frame having rear carrying wheels and a forward bearing roll

mounted in said frame, a shaft mounted transversely in said frame in the rear of said bearing roll, smoothing rolls mounted end to end on said shaft and having their abutting ends spaced apart, a pinion secured on said shaft between said smoothing rolls, a second shaft journaled in said frame in the rear of said smoothing rolls, handle bars pivoted on said second shaft, a driving shaft mounted in 10 said handle bars, and a driving connection between said driving shaft and said second shaft and said pinion.

6. A manually operated floor smoothing machine comprising a frame having side rails, a shaft journaled in said side rails, a bearing roll mounted in said rails in front of said shaft, a pinion secured on said shaft, smoothing rolls mounted on said shaft on each side of said pinion, a second shaft in 15 the rear of said first named shaft, a gear secured to said second shaft and meshing with said pinion, handle bars mounted on said second shaft and straddling said gear, a shaft mounted in said handle bars, a clutch and cog gear wheel having a balance wheel thereon and meshing with the gear of said second shaft, a driving shaft also journaled in said handle bars near the upper end thereof and having an operating crank and a 20 driving belt connection with said handle bar shaft, and said gears and driving connections being centrally located in said frame for applying the operating power centrally to said smoothing roll shaft.

35 7. A manually operated floor smoothing machine comprising a frame having side rails, a shaft journaled in said side rails, a bearing roll mounted in said rails in

front of said shaft, a pinion secured on said shaft, smoothing rolls mounted on said shaft 40 on each side of said pinion, a second shaft in the rear of said first named shaft, a sleeve mounted on said second shaft, a gear carried by said second shaft and meshing with said pinion, handle bars straddling said gear 45 and secured to said sleeve, a shaft mounted in said handle bars and operatively connected with said gear, and a driving shaft mounted in said handle bars and having a driving connection with said handle bar 50 shaft, said gears and driving connections being centrally located in said frame for applying the operating power centrally to said smoothing roll shaft.

8. A manually operated floor smoothing 55 machine comprising a frame, rolls journaled therein, abrading means mounted on the surfaces of said rolls, said rolls being of equal length and weight and arranged end to end, means for applying driving power to said 60 rolls between their abutting ends and midway between the outer ends thereof, means supporting the rear portion of said frame and handle bars for said frame, said handle bars adjustable as to height or angle and so 65 fulcrumed in relation to the weight of the machine that a small pressure on the handle will momentarily relieve the friction of the abrading rolls without stopping the machine.

In witness whereof, I have hereunto set my hand this 4th day of February 1915.

WILLIAM H. HAIGHT.
